ROLLING MILL

William J. Hill, Worcester, Mass., assignor to Morgan Construction Company, Worcester, Mass., a corporation of Massachusetts

Filed Oct. 10, 1969, Ser. No. 61,574
17 Claims. (Cl. 72—238)

This invention relates to a rolling mill and more particularly to apparatus having vertical rolls for the forming and attenuation of metal.

In a continuous rolling mill, it is advantageous at certain points in the rolling schedule to make use of a roll stand having vertical rolls. Such a vertical mill is shown in the U.S. Patent to Hill et al. No. 2,583,844. Among other beneficial aspects of the use of such a mill is the fact that it does away with the necessity of twisting the material to be rolled. However, certain problems arise in the construction and use of a vertical mill that are not encountered in the design of a horizontal mill. One serious problem encountered with such a mill is that, in order to repair or replace the elements associated with the rolls and the driving connection, it is usually necessary to remove them vertically; the spindles, for instance, can usually only be removed by first withdrawing the guide frames with the spindles suspended from them; a very high building is required in order to support a crane capable of clearing the guide frames and the suspended spindles from the top of the mill housing. A building of this sort is extremely expensive and, of course the crane must have a weight-carrying ability equal to the weight of the guide frames and the spindles along with the associated couplings etc. Furthermore in vertical mills of this type in the past the sliding surfaces existing between the supporting base posts and the mill frame have been exposed and subject to considerable maintenance difficulty. It will be understood that any difficulty or delay in replacing rolls, couplings, spindles, and similar elements of the mill causes the mill "down-time" to be increased with the result that on occasion the entire continuous mill must await the completion of the work on a single vertical roll stand. This results in a very unsatisfactory economical situation in that very large capital assets are unproductive for the length of time that the mill is out of operation. These and other difficulties experienced in the prior art devices have been obviated in a novel manner by the present invention.

It is, therefore, an outstanding object of the invention to provide a rolling mill of the vertical type in which the overhead height needed for disassembly of the rolls and drive elements is reduced to a minimum.

Another object of this invention is the provision of a vertical rolling mill having an improved and novel supporting structure.

It is another object of the instant invention to provide a vertical rolling mill having novel structure for suspending the drive spindles.

It is a further object of the invention to provide a vertical rolling mill having a simple and rugged construction which will be capable of a long life of useful service, but, nevertheless, requires only a short time for the disassembly and replacement of parts.

A still further object of this invention is the provision of a vertical rolling mill in which the rolls and spindles are carried in a vertical guide member and in which it is not necessary to disconnect complicated hydraulic systems for the roll bearings in order to remove the spindles and couplings.

With these and other objects in view, as will be apparent to those skilled in the art, the invention resides in the combination of parts set forth in the specification and covered by the claims appended hereto.

The character of the invention, however, may be best

2

understood by reference to certain of its structural forms as illustrated by the accompanying drawings in which:

FIG. 1 is a perspective view of the rolling mill embodying the principles of the present invention;

5 FIG. 2 is a front elevational view of the invention;

FIG. 3 is a side elevational view of the invention;

FIG. 4 is a perspective view of a base portion of the invention;

FIG. 5 is an exploded perspective view of the mill;

10 FIG. 6 is a view of the mill taken on the line VI—VI of FIG. 2;

FIG. 7 is a horizontal sectional view of the mill taken on the line VII—VII of FIG. 2;

FIG. 8 is a perspective view of a guide rail of the mill;

15 FIG. 9 is a perspective view of a shelf, or "third chock" and spindle of the mill;

FIG. 10 is a sectional view taken on the line X—X of FIG. 9; and

FIG. 11 is a sectional view taken on the line XI—XI of 20 FIG. 9.

Referring first to FIGS. 1, 2 and 3 wherein are best shown the general features of the invention, it can be seen that the rolling mill, indicated generally by the reference numeral 10, is mounted on a concrete foundation 11.

25 The mill consists generally of a housing structure 12 mounted for vertical movement on a base 13 and driven by a motor (not shown) through a pinion and gear drive housing 14 located in a well or cellar 19 formed in the foundation 11. Two rolls 15 and 16 are mounted in the

30 housing structure 12 and are driven by spindles 17 and 18 respectively which connect the drive housing 14 to the rolls. The cellar 19 formed in the foundation 11 to hold the drive housing 14 is provided with passages 21 and 22 which lead out of the cellar for various purposes. From

35 FIG. 3 one looks through the passage 22 where the input shaft 23 of the gear drive is evident. The drive housing 14 contains the usual bevel gear and mill pinions for speed reduction for right angle change of direction and for division of input power between the two spindles 17 and 18.

40 Such gearing is well known and does not form a part of the present invention.

Mounted at one end of the housing structure 12 on the upper surface of the foundation 11 is a motor 24, shown in FIG. 1, which is connected through a gear unit 25 to a

45 generally vertical spindle 26 which drives the roll adjusting mechanism on one side of the mill. In a similar way, a motor 27, shown in FIG. 3, is mounted on the base 11 and is connected through a gear unit 28 to a spindle 29 which drives the roll adjusting mechanism on the other

50 side of the mill. One end of the housing structure 12 is provided with a ladder 31, shown in FIGS. 1 and 2, to assist the operator in climbing to the upper surface of the housing. Furthermore, guard rails 32, 33 and 34 extend around the edge of the upper surface of the housing structure 12 to prevent the operator from falling off. In FIG.

55 1 it can be seen that the roll 15 is mounted in a pair of chocks 35 and 36 and that the upper chock 35 is provided with pivoted links 37 and 38 to which a crane may be attached. In the same way, the roll 16 is mounted in a

60 pair of chocks 39 and 41 and the upper chock 39 is provided with pivoted links 42 and 43. Evident in FIGS. 1, 2, 6 and 7 are guide rails 44 and 45 into which the chocks 35 and 36 and chocks 39 and 41, respectively, are slidably lowered.

65 Referring now to FIG. 4, which shows the construction of the base 13, it can be seen that a rectangular sub-frame 46 is provided consisting of two side members 47 and 48. Joining these two side members are two end members 49 and 51 from which upwardly extend, respectively,

70 posts indicated generally at 52 and 53. The end members 49 and 51 are also joined together by girder members 54 and 55. Each of the posts 52 and 53 is of elongated verti-

cal form and is of generally rectangular cross-section with the long dimension extending parallel to the roll pass and normal to the associated end member. The post 52 is provided with a vertical slot 56, and the post 53 is provided with a similar slot 57. The upper ends of the posts 52 and 53 are provided with suitable grooves indicated at 124 and 126 respectively which open into the slots 56 and 57 to provide for the introduction of blocks 66 and 68 (see FIG. 6) which when properly bolted in place render the posts substantially solid. The girder members 54 and 55 are provided with upper horizontal surfaces 58 and 59, respectively, to receive the rolling mill guide stand. While the posts 52 and 53 have hereinbefore been described as being vertically slotted at 56 and 57, it will be understood that they may be described as two pairs of posts, the posts of each pair being spaced in the direction of the pass line.

To the opposite sides of the post 52 are attached finely machined plates 61 and 62, while similar pair of plates 63 and 64 are fastened to the opposite sides of the post 53. These plates extend outwardly from the surfaces of their posts to provide guide surfaces to contact mating surfaces in the housing structure 12 to facilitate vertical sliding.

Referring now to FIG. 5, which is the exploded view of some of the important elements of the mill, there is provided a graphic illustration of the manner in which the elements are assembled and disassembled. The housing structure 12 slides downwardly over the posts 52 and 53 of the base 13. Then, the guide rails 44 and 45 slide downwardly into the housing structure. Third chocks 97, 97a carrying their respective universal drive spindles 17 and 18, slide down the guide rails 44 and 45 until stopped by the upper edge of web 92 as hereinafter described. The chocks 97 and 97a are thus rigidly attached to the guide rails 44 and 45 and act as supporting shelves at the lower ends of the guide rails. Following that, the chocks 35 and 36 with the roll 15 slide downwardly into operative position along the guide rail 44, while the roll 16 with its pair of chocks 39 and 41 slides downwardly into operative position along the guide rail 45.

In FIG. 6, which is a plan view of the mill, it can be seen that the upper part of the housing structure 12 is provided with an elongated rectangular window 65. The rolls 15 and 16 are shown mounted, respectively, in their upper chocks 35 and 39. The post 52 is shown extending upwardly through a roll housing outer window 128. The window 128 is shown as having finished parallel vertical surfaces which engage the plates 61 and 62. In this view it can be seen that block 66 is inserted at the upper end of the slot 56 and that a bolt 67 holds the post 52 and block 66 in a rigid assembled unit. In a similar way, at the other end of the housing 12 is located a roll housing outer window 130 in which is located the post 53 here shown provided with a block 68 inserted at the upper end of the slot 57, there being a bolt 69 extending through the block 68 and post 53 to provide a rigid unit. Window 130 has finished parallel surfaces which engage plates 63 and 64. The upper chock 35 is provided on opposite sides with grooves 71 and 72 which, as shown in FIGS. 6 and 7, are engaged by guide rail flanges 73 and 74. The flanges 73 and 74 are integral with guide rail 44 and are connected to hydraulic linear actuators 75 and 76, the guide rail flanges and actuators acting on the chock grooves 71 and 72 to constitute a roll pull back device. The lower chock 36 is provided with grooves (not shown) similar to the grooves 71 and 72. In the same way, chock 39 is provided with grooves 77 and 78 which engage guide rail flanges 79 and 81 integral with guide rail 45 which is connected to hydraulic linear actuators 82 and 83. Lower chock 41 is provided with grooves (not shown) similar to grooves 77 and 78. Similar hydraulic linear actuators are applied to guide rails 44 and 45 in connection with the chocks 36 and 41 at the lower ends of the rolls.

Referring now to FIG. 7, which is a sectional view through the mill 10 at a slightly lower level than FIG. 6, it can be seen that the post 52 is provided with its own separate window 128, while a similar window 130 is provided for the post 53. It will be noted that both of these windows 128 and 130 are, in the described embodiment, separate from the main window 65 in which reside the rolls 15 and 16 but are contained within the limits of the housing structure 12. The spindle 26 extends vertically through the housing structure 12 and is connected by gears to a roll chock positioning screw 36. The screw is provided with threads which engage a threaded nut 87 locked in the housing structure. The inner end of the screw 36 contacts the chock 39 to move it laterally, passing through an opening in the guide rail 45. In the same way, the spindle 29 extends vertically adjacent the housing 12 and is connected by a set of gears to a screw 38 which has a mating nut 89. The inner end of screw 38 engages the chock 35 through an opening in the guide rail 44. It will be understood that a similar set of screws (not shown) driven by spindles 29 and 26 respectively will be provided for the actuation of the lower chocks 36 and 41.

FIG. 8 shows the specific construction of the guide rail 44 which is provided with flanges 73 and 74 whose cross-section shape has been shown in FIGS. 5, 6 and 7. The guide rail 44 is provided with a backing member 91 which joins the rear edges of the flanges 73 and 74. The inner edges of the flanges 73 and 74 are joined at the lower end by a web 92, and a bottom 93 is joined to the bottom edges of the flanges, backing member and web. A small opening 94 is provided in the lower end of the flange 73 to release water, scale and the like. Guide rail 45 is constructed in the same manner as guide rail 44.

In FIG. 9, which shows the elements associated with the spindle 17, it can be seen that the spindle is provided at its lower end with a spherical gear coupling 95 and at its upper end with a similar spherical gear coupling 96. This coupling 96 is supported from a third chock 97 which is provided with ears 98 and 99 which in turn are provided respectively with grooves 101 and 102 exactly similar to the grooves 71 and 72 formed on the chock 35. The configuration of the ears 98 and 99 with their grooves 101 and 102 permits them to be lowered into and be slidably engaged by the flanges 73 and 74 of the guide rail 44 in exactly the manner in which both upper and lower roll chocks 35 and 36 slide downwardly into and along the rail. The motion of the third chock downwardly is limited by the engagement of upper edge 132 of the web 92 with the undersurface of the third chock 97. In operative condition, it will be noted that the third chock 97 lies under and supports the lower chock 36 of the roll 15.

In FIG. 10, which is a sectional view through the third chock 97 on the line X—X of FIG. 9, it is possible to see the manner in which the flanges 73 and 74 of the guide rail 44 engage the ears 98 and 99 and reside in the grooves 101 and 102 of the third chock 97.

FIG. 11 shows the manner in which the roll 15, the lower chock 36, the third chock 97, the coupling 96, and the spindle 117 are related. The roll 15 is provided with a roll neck 103 having a tapered portion 104 on which is mounted the sleeve 105 of an oil film bearing of the type shown and described in the U.S. patent to Dahlstrom, No. 2,018,055. A bushing 106 of the bearing is mounted in the lower chock 36 in the usual manner. The bearing is provided with an upper seal 107 to prevent entrance of foreign matter and is connected to an oil supply in a manner well known in the art. At its lower end the bearing is provided with a thrust bearing 107. The lower end of the roll neck 103 is formed with the usual non-circular wobbler, one of the flat faces being shown as at 103', and this fits into a similarly-shaped pocket 108 formed within an intermediate member 109. The intermediate member resides in a bore within the third chock

97. The intermediate member 109 is provided with an outwardly extending annular flange 111 which overlies an inwardly-extending annular flange 112 formed on the inner surface of the third chock. Interposed between the flanges 111 and 112 is a roller thrust bearing 113 permitting free rotational movement of the intermediate member 109 within the third chock 97. Suitable sealing is provided at the upper end of the third chock and of the intermediate member to assure that water and foreign matter cannot gain entrance into the third chock. For instance, downwardly-extending annular flanges 113 and 114 are alternated with upwardly-extending flanges 115 and 116 on the upper end of the third chock. The lower end of the intermediate member 109 is fastened to the male member 117 of the spherical gear coupling 96, while the female member is mounted on a coupling box 118 which in turn, is fastened to the upper end of the spindle 17.

An electric motor 119, shown in FIG. 1, is fastened to the upper surface of the foundation 11 to operate two interconnected vertical jacks 121 and 122, shown in FIG. 4, to engage the under-surface of the housing structure 12 to move it upwardly and downwardly.

The operation of the rolling mill of the invention will now be readily understood in view of the above description. When assembled in the manner shown in FIG. 1, the operation of the mill is not unlike vertical mills known in the past. Power enters the system through the drive housing 14 and is transmitted through the spindles 17 and 18 (see FIG. 2) to the rolls 15 and 16. Universal movement between the rolls and the spindles for misalignment due to lateral adjustment of the rolls is permitted by the spherical gear coupling 96 as well as the spherical gear coupling 95 at the lower end of the spindle 17. Mis-alignment between the drive housing 14 and the base 13 is also compensated for since the drive spindles 17 and 18 depend directly from the universal couplings associated with the third chocks which may be positioned a substantial distance above the drive housing. In the case of the spindle 17, the power passes through the spherical gear coupling 96 to the intermediate member 109 and from there to the wobbler section of the roll 103 and thence to the roll 15. Each of the chocks contains an oil film bearing similar to the bearing formed by the sleeve 105, and the bushing 106 of the roll neck 103 and the chock 36. Adjustment of the rolls toward and away from one another takes place by energizing the motors 24 and 27, seen in FIGS. 1 and 2, thus rotating the spindles 26 and 29; this produces horizontal movement of the screwdowns 86 and 88 against the chocks in the usual manner. Vertical movement of the housing structure 12 and the rolls is accomplished by energizing the motor 119 which drives jacks 121 and 122. The vertical movement is permitted by splined connections between universal couplings 95 and 95a positioned respectively at the lower ends of the spindles 17 and 18 and the pinions contained in drive housing 14 (see FIG. 5). Attached to the upper chock 35 is roll adjustment means similar to that shown in the patent application of Hili, Serial Number 768,983, filed October 22, 1958 and now U.S. Patent No. 3,003,836; by this roll adjustment means it is possible to adjust one roll vertically relative to the other to align grooves formed on the surface of the roll. If the chocks 35, 36, 39 and 41 are provided with oil film bearings, these must be supplied with oil. In such case, the oil conduits for these chocks are contained within the corresponding guide rails 44 and 45, although for the purpose of clarifying the description and simplifying the drawings, these conduits have not been shown. It is contemplated that a simple connection between these conduits and the oil passages in the chocks be used to facilitate removal of the rolls and chocks as the rails 44 and 45 remain in the housing. It is important that it be possible to assemble and disassemble the elements of the mill very quickly, since "down-time" is expensive to the operator of the mill. In

disassembling the mill, the housing structure 12 is moved to its lowest position on the posts 52 and 53 (see FIGS. 4 and 5). This will be accomplished by lowering the jacks 121 and 122.

5 Referring to FIG. 5, when the housing structure 12 has been moved to its lowest position on the posts 52 and 53, it is possible, by attaching a crane to the pivoted links 37 and 38 on the chock 35, and to pivoted links 42 and 43 of chock 39, to withdraw in a single crane lift both rolls 10 15 and 16 with their chocks 35, 36, 39 and 41. The chocks 35 and 36 will slide along the flanges 73 and 74 (see FIGS. 6 and 7) of the guide rail 44. Similarly chocks 39 and 41 are guided during removal by flanges 79 and 91 of guide rail 45. Incidentally, before removing the rolls, it is necessary to disconnect the oil supply pipe connections to the individual chocks when oil filled bearings are used, and to withdraw keeper plates, a relatively simple operation. If it is only necessary to change the bearings or the rolls, these steps are all that is needed in disassembly. If, however, it is desired to replace one of the couplings associated with the drive spindles 17, then the spindle 17 and the third chock 97 can be withdrawn as a subassembly by the crane, the third chock 97 being guided in the flanges of the guide rail 44 and the spindle 17 hanging downwardly. The spindle 18 and its associated third chock 97a can be removed in the same way. If further disassembly is desired, the guide rails 44 and 45 may be removed upwardly readily after disconnecting the hydraulic separators 75, 76, 82, 83, and after 20 moving the rails toward the center of the housing so that the screws 88 and 86 respectively (see FIG. 7) do not extend through the normal apertures formed in the backs 91 of the guide rails. Then, of course, further disassembly can take place by removing the housing structure 12 itself. In any case, the amount of overhead clearance that needs to be available in the mill building to permit removal of any of these parts is never greater than the height of the housing structure itself; for instance, one can see that the unit presented by the chock 35, the roll 25 30 35 40 45 50 55 60 65 70 75 80 85 90 95 100 105 110 115 120 125 130 135 140 145 150 155 160 165 170 175 180 185 190 195 the posts 52 and 53 lay in the ends of the window 65, which construction is an obvious alternative; in other words, the posts are inside of the housing structure rather than outside as has been known in the past and the benefits from the point of view of stability are obvious. Other advantages, of course, are that the finished surfaces which guide the housing structure 12 on the posts are covered at all times and lie within the mill rather than being exposed to the dirt and scale which are normally found in a steel mill.

The invention having been thus described, what is claimed as new and desired to secure by Letters Patent is:

1. A vertical rolling mill, comprising a housing structure having two windows disposed in vertically-spaced parallel relationship, a pair of roll chocks positioned in each window, a pair of guide rails extending through one window and into the other window, one chock of each pair being slidable vertically on each guide rail for movement into and out of the window, a roll journaled in the chocks carried by each guide rail, a drive spindle extending downwardly beneath each roll, a base underlying the housing structure, two posts rigidly attached to and extending upwardly from the base, said posts residing in opposite ends of the housing structure in small windows provided therefor, each post being of generally rectangular horizontal cross-sectional form and having its larger dimension extending transversely of the large windows, each post having a vertical slot extending therethrough longitudinally of the large windows, roll positioning screws mounted in the housing structure and extending through the slots into operative relationship with the chocks, a third chock means detachably joining each third chock to a guide rail, and an intermediate member rotatably carried by each third chock and serving to connect the roll to the spindle.

2. A vertical rolling mill, comprising a mill housing having a first window and a second window disposed in vertically spaced parallel relationship, a pair of roll chocks positioned in each of said windows, a pair of guide rails extending through said first window and into said second window, said chocks being slidable vertically on said guide rails respectively for movement into and out of the said windows, a roll journaled in the chocks carried by each guide rail, a shelf in the form of a third chock slidable on each rail and extending laterally thereof toward the other rail, each shelf being normally located beneath the roll chock at the lower end of its rail, and a drive spindle supported by and depending from each shelf.

3. A vertical rolling mill, comprising a mill housing having a first window and a second window disposed in vertically spaced parallel relationship, a pair of roll chocks positioned in each window, a pair of guide rails extending through said first window and into said second window, said chocks being slidable vertically on said guide rails respectively for movement into and out of said windows, a roll journaled in the chocks carried by each guide rail, a drive spindle extending downwardly beneath each roll, a third chock including a universal coupling joining each spindle to its roll in driving relationship, and means detachably joining each third chock to a guide rail.

4. A vertical rolling mill, comprising a substantially rigid integral mill housing having a first elongated window and a second elongated window disposed in vertically spaced parallel relationship, two pairs of roll chocks, each pair having a first chock positioned in said first window and a second chock positioned in said second window, two rolls, each roll being journaled in a said pair of chocks, a base underlying the housing, two posts extending upwardly from the base, the posts residing at opposite ends of the mill housing in windows provided therefor, each post being of generally rectangular horizontal cross-sectional form and having its larger dimension extending transversely of the windows, each post having a vertical slot extending therethrough longitudinally of the windows, and screws

mounted in the structure and extending through the slots into operative relationship to the chocks.

5. A vertical rolling mill, comprising a mill housing having first and second horizontal elongated windows disposed in vertically spaced parallel relationship and having first and second vertical windows disposed in horizontally spaced parallel relationship, two pairs of roll chocks, each pair having one chock positioned in said first horizontal window and one chock positioned in said second horizontal window, two rolls, each roll being journaled in a pair of chocks, a base underlying the housing and comprising support members at opposite ends thereof, posts rigidly attached to and extending upwardly from the said members, and two parallel girder members joining the ends of the support members in rigid relationship, the girder members being located outside the vertical projection of the housing and being adapted to carry guides independently of said housing.

20 6. A vertical rolling mill, comprising a mill housing having first and second large elongated windows disposed in vertically spaced parallel relationship, a pair of roll chocks positioned in each of said windows, a pair of guide rails extending from said first window into said second window, said chocks being slidable vertically on said guide rails for movement into and out of the windows, a roll journaled in the chocks carried by each guide rail, a base underlying the housing, two posts rigidly attached to and extending upwardly from the base, the posts residing in opposite ends of the mill housing in small windows provided therefor, each post being of a generally rectangular horizontal cross-sectional form and having its larger dimension extending transversely of the large windows, each post having a vertical slot extending therethrough longitudinally of the windows, screwdowns mounted in the housing extending through the slots into operative relationship with the chocks, a drive spindle extending downwardly beneath each roll, a third chock including a universal coupling joining each spindle to its roll in driving relationship, and means detachably joining each third chock to a guide rail.

40 7. A vertical rolling mill, comprising a mill housing having first and second large elongated windows disposed in vertically spaced parallel relationship, a pair of roll chocks positioned in each said windows, two rolls, each roll being journaled with one chock in each window, a base underlying the housing and comprising two spaced support members, each support member having a post, the posts residing in opposite ends of the mill housing in small windows provided therefor, each post being of generally rectangular horizontal cross-sectional form and having its larger dimension extending transversely of the large windows, the support members extending transversely of the windows in spaced parallel relationship, a girder member joining each pair of ends of the support members in rigid relationship, said girder members being located outside of the vertical projection of the housing and being adapted to carry guides independently of the said housing, each said post having a vertical slot extending therethrough longitudinally of the large windows, and roll positioning screws mounted in the housing and extending through the slots into operative relationship with the chocks.

60 8. A vertical rolling mill comprising a mill housing having first and second large elongated windows disposed in vertically spaced parallel relationship, a pair of roll chocks positioned in each of said windows, a pair of guide rails extending downwardly through said first window and into said second window, one chock of each pair being slidable vertically on each guide rail for movement into and out of the said windows, a roll journaled in the chocks carried by each guide rail, a drive spindle extending downwardly beneath each roll, another chock including a universal coupling joining each spindle to its roll in driving relationship, means detachably joining said last-named chock to a guide rail, a base comprising two spaced support members underlying the housing, a post extending

upwardly from each of said support members, the support members extending transversely of the windows in spaced parallel relationship, and girder members joining the ends of the support members in rigid relationship, the girder members being located outside the vertical projection of the housing and being adapted to carry guides independently of said housing.

9. A vertical rolling mill, comprising a mill housing having first and second large elongated windows disposed in vertically spaced parallel relationship, two pairs of roll chocks, each pair having one chock positioned in each of said windows, a pair of guide rails extending downwardly through said first window and into said second window, the chocks of each pair being slidable vertically on one of the guide rails for movement into and out of the said windows, a roll journaled in the chocks carried by each guide rail, a drive spindle extending downwardly beneath each roll, another chock including a universal coupling joining each spindle to its roll in driving relationship, means detachably joining said last-named chock to a guide rail, a base comprising two spaced parallel support members and underlying the housing, a post rigidly attached to each support member and extending upwardly therefrom, the posts residing at opposite ends of the mill housing in small windows provided therefor, each post being of generally rectangular horizontal cross-sectional form and having its larger dimension extending transversely of the large windows, each post having a vertical slot extending therethrough longitudinally of the large windows and screw-downs mounted in the housing and extending through the slot into operative relationship with the chocks, and girder members joining the ends of the support members in rigid relationship, the girder members being located outside the vertical projection of the housing and being adapted to carry guides independently of the said housing.

10. A vertical rolling mill, comprising a mill housing having a pair of windows disposed in vertically spaced horizontal parallel relationship, a pair of roll chocks positioned in each window, a pair of guide rails extending through one window and into the other window, one chock of each pair being slidable vertically on each guide rail for movement into and out of the windows, a roll journaled in the chocks carried by each guide rail, a third chock slidable on each rail and extending laterally thereof toward the other rail, each third chock being normally located beneath the roll chock at the lower end of its rail, a drive spindle supported by and depending from each third chock, an intermediate member carried in bearings in each third chock for rotation therein, the lower end of a roll separably connected to the upper part of the intermediate member, the lower part of each intermediate member being connected through a universal coupling to the upper end of the drive spindle.

11. A vertical rolling mill, comprising a mill housing having two windows disposed in vertically spaced parallel relationship, a pair of roll chocks positioned in each window, a pair of guide rails extending through one window and into the other window, one chock of each pair being slidable vertically on each guide rail for movement into and out of the windows, a roll journaled in the chocks carried by each guide rail, a third chock, a drive spindle extending downwardly beneath each roll and supported by means associated with said third chock, means detachably joining each third chock to a guide rail, and an intermediate member rotatably carried by each third chock and serving to connect the roll to the spindle.

12. A vertical rolling mill, comprising a mill housing having a pair of windows disposed in vertically spaced parallel relationship, a pair of roll chocks positioned in each window, a pair of guide rails extending through one window and into the other window, one roll chock of each pair being slidable vertically on each guide rail for movement into and out of the windows, a roll journaled in the roll chocks carried by each guide rail, a third chock slidable on each rail and extending laterally toward the

other rail, each third chock being normally located at the lower end of its rail, a drive spindle supported by and depending from each third chock, an aperture in each rail in a position corresponding to each roll chock associated therewith, and a roll positioning screw extending through each aperture for engagement with a roll chock.

13. A vertical rolling mill, comprising a unitary rigid roll housing having vertical and horizontal intersecting passages therethrough, a pair of oppositely disposed facing removable guide rails vertically positioned in said vertical passage, a pair of roll units, each unit comprising a vertical roll and associated upper and lower chocks, means on said chocks of each unit for making slidable engagement with one of said guide rails whereby said roll units can be lowered into operative position on said rails in said vertical passage and aligned with said horizontal passage, a base and means associated therewith for securing said housing thereto, said means comprising two posts at each end of said base, each pair of said posts extending upwardly through said housing between a guide rail and one end of said housing, the upper ends of each pair of posts being rigidly connected by a removable bracing element to provide the equivalent of a one-piece vertically slotted post, and means mounted on said housing and passing through the slotted post for adjusting the horizontal position of the said guide rails and associated roll units.

14. Means for mounting a mill housing of the type adapted to carry vertical rolls therein in a manner to permit vertical adjustment of said housing with respect to a fixed base while precluding appreciable movement of the housing in the direction of or horizontally transverse to the pass line, said means comprising two pairs of posts fixed to said base and extending upwardly through vertical passages which are within the confines of said housing and in close sliding relation therewith, each said pair of posts being transversely aligned with the rolls when the rolls are operatively positioned in said housing, said posts extending above the top of said housing, a removable block securing together the upper ends of each pair of posts to measurably increase the rigidity of each pair of posts without eliminating the vertical space between said posts therebelow, said vertical space providing a passage through which roll adjusting means may extend.

15. A vertical rolling mill, comprising a supporting base which includes two pairs of fixed vertical parallel spaced posts, the pairs of posts located on opposite sides of the pass line, a roll housing carried by said base and held against horizontal movement by said posts which extend upwardly through suitable vertical passages in said housing, upper and lower windows in said housing between said pairs of posts, two vertically extending removable rail guides in said windows, three chocks removably carried by each rail guide, the bottom chocks carrying drive spindles which extend below said housing, the middle and upper chocks carrying a roll, means for operatively connecting each said roll to its spindle, removable bracing means securing the upper ends of said posts, roll adjusting screws operatively mounted on said housing beyond said posts and extending toward the pass line between said posts to said guide rails, the vertical dimensions of said posts, said housing, said guide rails, said bottom chock and spindle, and said rolls and related chocks being of generally the same order of magnitude whereby all parts may be removed from said base by vertical lifting through a distance only slightly greater than the vertical dimension of the housing.

16. A vertical rolling mill, comprising a base including oppositely disposed vertical posts, a roll housing and vertical rolls supported by said base with said posts extending upwardly through vertical openings in said housing located near the opposite ends of said housing, the said posts fitting snugly within said openings and being sufficiently strong and rigid to prevent movement

11

of said housing in a horizontal direction during operation of the mill.

17. A vertical rolling mill as set forth in claim 16, each said post being vertically slotted through most of its length but connected at the upper end, the slot being 5 aligned with a plane passing through the axes of the rolls.
